United States Patent Office

Des. 212,206

Patented Sept. 17, 1968

212,206

TIE SUPPORT

Robert B. Rietman, 3434 Manor Hill Drive,
Cincinnati, Ohio 45226

Filed May 22, 1967, Ser. No. 7,211

Term of patent 14 years

(Cl. D2—359)

Fig. 1

Fig. 2

Fig. 3

Fig. 4

Fig. 5

FIG. 1 is a front elevational view of a tie support showing my new design;

FIG. 2 is a rear elevational view thereof;

FIG. 3 is a side elevational view;

FIG. 4 is a front perspective view; and

FIG. 5 is a rear perspective view.

I claim:

The ornamental design for a tie support, substantially as shown.
